UNITED STATES PATENT OFFICE.

JOSEPH BETHENOD AND MARIUS LATOUR, OF PARIS, FRANCE.

DOUBLY-TUNED WIRELESS RECEIVER.

Application filed August 19, 1921. Serial No. 493,680.

To all whom it may concern:

Be it known that we, JOSEPH BETHENOD and MARIUS LATOUR, citizens of France, and residents of Paris, France, have invented 5 certain new and useful Improvements in Doubly-Tuned Wireless Receivers, of which the following is a specification accompanied by drawings.

This invention relates to a receiving 10 arrangement for wireless telegraphy and telephony adapted to decrease the influence of disturbing or atmospheric currents.

In accordance with this invention, two 15 analogous receiving circuits are balanced by over and under tuning, i. e. by tuning one to too great a wave length and the other to too short a wave length as compared to the signal. From this it follows that for continuous waves this balancing connection be- 20 comes essentially a phase connection because of the detunings in the contrary sense, of the two circuits with respect to these waves, while for an instantaneous or sudden discharge, this constitutes a balanc- 25 ing connection.

The invention is shown in Figure 1.

Fig. 2 shows a modification.

Fig. 1 illustrates an antenna or frame 1 which may be tuned by means of a capacity 30 to a wave length to be received. Preferably, the circuit of this frame or loop is damped either by a series resistance or by a resistance in shunt with the capacity 2. Furthermore, a resistance may be provided 35 in shunt in a suitable manner that is a function of the potential at the terminals of the condenser (detector, valves, etc.) so that the damping be greater in proportion to the value of this potential. The primary cir- 40 circuit 1—2 controls the secondary receiving circuits 3 and 5, the secondary capacities 4 and 6 of which are adjusted in such a manner that while one of them is tuned to a wave length that is longer than the wave 45 to be received, the other is tuned to a shorter wave length. From the standpoint of the wave received under these conditions, one of the capacities permits the passage of a current that is in a lagging phase and the 50 other permits a passage of a current that is in a leading phase.

As a result of this, if the inductances are in opposition (from the standpoint of the mutual induction with the primary circuit), 55 the two currents received will reinforce each other. On the other hand, with a sudden

discharge, the mutual induction of the two opposed circuits is very much reduced and may even be made equal to zero.

The double coil 7 and the capacity 8 make 60 possible the tuning of the ensemble of the secondary system to the length of the wave to be received before it actuates the lamp amplifier or detector 9 or generally speaking, an amplifier provided with multiple 65 resonances. It should be noted that, in each element 3—4, 5—6 of the secondary receiving circuit, the atmospheric discharges assume a different wave length from the receiving. As a whole, the above described 70 permits of adding to the advantages obtained through the differentiation of the disturbing currents and the currents to be received either by damping the antenna or by detuning the receiver as disclosed in 75 French Patent 502,279 of Marius Latour.

The same reasoning that applies to high frequency applies also to musical or low frequency. The amplification of the musical current resulting from the receiving at 80 a station and responding to a given tone may be accomplished in the following manner: Two receiving circuits are balanced and tuned to the different tones, one lower and 85 the other higher than the tone received.

Two distinct primary receivers may be provided instead of two secondary receivers, by utilizing two frames or loops. Under certain conditions, these arrangements may be advantageous. In accordance with 90 Figure 2, two frames are used, 1 and 2, being situated in parallel planes. In accordance with the present invention the mutual inductance of this frame is compensated by an artificial mutual inductance 3. These 95 two frames actuate in an inverse sense through the agency of coils 4 and 5 a single secondary circuit tuned by means of the capacity 8 to the wave length to be received. The two frames 1 and 2 are tuned, one above 100 and the other below, to the wave length to be received, i. e. the fact is taken in consideration that for continuous waves of known frequency the currents will add to a certain phase relation, while for an instantaneous discharger the currents will oppose. The advantages of detuning of the receiving circuit described in French Patent Number 105 502,279 are always retained.

In many cases it will be advantageous to 110 vary the damping of the high frequency circuits and this may be done by changing

the values of the resistances 10 and 11, as shown in the drawing, or by other means.

Having described our invention, what we claim is:

1. In wireless signalling systems, a circuit tuned to a frequency greater than the signal frequency and a second circuit tuned to a frequency lower than the signal frequency, and means for opposing the currents in said circuits to prevent response of said system to sudden discharges.
- 10 2. In wireless signalling systems, an antenna tuned to the signal frequency, a secondary circuit connected thereto through only two independent couplings one coupling being over tuned and the other under tuned in respect to the signal frequency and a receiver connected to said secondary circuit.
- 15 3. In wireless signalling systems, an antenna tuned to the signal frequency, a secondary circuit connected thereto through only two independent couplings, one coupling being over tuned and the other under
- 20 tuned in respect to the signal frequency and
- 25

means for varying the damping of the high frequency circuits.

4. In wireless signalling systems, the combination of an antenna circuit tuned to signal frequency, a secondary circuit tuned as a whole to signal frequency and said secondary circuit comprising two separate portions, one tuned to a frequency lower than signal frequency and the other tuned to a frequency higher than signal frequency and each comprising means coupled to said primary circuit.

5. In wireless signalling systems, the combination of an antenna circuit tuned to signal frequency, a secondary circuit tuned as a whole to signal frequency and said secondary circuit comprising two separate portions, each portion comprising inductance and capacity, one of said portions being tuned to a frequency below signal frequency and the other being tuned to a frequency above signal frequency and each portion being coupled to said antenna circuit.

JOSEPH BETHENOD.
MARIUS LATOUR.
